(57) **CLAIM**

The ornamental design for a main body for built-in oven range, as shown and described.

DESCRIPTION

1. Main body for built-in oven range

1.1 is a front perspective view of a main body for built-in oven range;

1.2 is a front view thereof;

1.3 is a back view thereof;

1.4 is a left view thereof, where the right view is a mirror image;

1.5 is a top view thereof;

1.6 is a bottom view thereof; and

1.7 is a bottom perspective view thereof.

The dash-dash broken lines depict portions of the main body for built-in oven range that form no part of the claimed design. The dash-dot broken lines define the boundary of the claimed design and form no part thereof.
